SHUTTLE CHECK

Carl D. Brown, Hopedale, Mass., assignor to
 Draper Corporation, Hopedale, Mass., a corporation of Maine

Application September 17, 1935, Serial No. 40,948

5 Claims. (Cl. 139—186)

The present invention pertains to shuttle checks for fly shuttle looms, and has more particular reference to the type of shuttle check embodying a shuttle engaging binder.

5 The conventional loom binder is engaged by the shuttle as the latter enters the shuttle box, the binder being spring-pressed toward the shuttle to thereby check the same. As commonly constructed, the binder is pivoted to the lay at 10 its outer end, with the result that, in the absence of exceptionally accurate adjustment of the shuttle box and binder, the area of the contact between the binder and the shuttle is quite small. It has been proposed to provide a floating binder 15 having contact with the shuttle over a much greater area, thereby increasing the checking action of the binder. However, such floating binders have not been generally used, the constructions embodying the same having been impractical for various reasons.

20 The present invention has for its object to provide, in a shuttle box having a floating binder, simple and efficient means for controlling the binder to enable the latter to effectively check the shuttle. To the end mentioned, there is provided and herein disclosed a friction means for opposing movement of the binder by the incoming shuttle, such means comprising a flexible strap frictionally engaging a friction surface on 25 the binder.

25 The preferred embodiment of the invention is illustrated on the accompanying drawing, of which:

30 Fig. 1 is a plan view of one end of the lay of a loom comprising said embodiment;

35 Fig. 2 is a view similar to Fig. 1 but with the shuttle fully entered in the shuttle box;

40 Figs. 3 and 4 are, respectively, front and rear elevations of the outer end of the lay and shuttle box; and

45 Fig. 5 is a view of the binder in cross-section taken through the spring aperture.

The loom to which the drawing relates is of conventional design except as to the shuttle box and shuttle check. Accordingly, there is herein disclosed only the shuttle check of the present invention, and certain conventional parts closely associated therewith. Of the conventional parts, only the left hand portion of the lay 1 is shown 50 on the drawings. The lay reciprocates forwardly and rearwardly in the usual manner, the front of the loom being toward the bottom of the sheet, Figs. 1 and 2.

55 The lay is provided with a shuttle box shown as comprising a front box plate 2 and a back box

plate 3, it being understood that a shuttle box may also be provided at the other end of the lay. The shuttle box opens inwardly of the loom whereby the shuttle 4 may be picked along the lay into and out of the shuttle box. Conventional shuttle picking means may be employed, there being shown on the drawing the usual picker stick 5 having a picker 6 mounted directly thereon.

5 The shuttle box is provided with a binder 7 which is adapted to be engaged and moved by the shuttle as the latter enters the shuttle box. The binder is movable generally laterally of the shuttle box and is adapted to retard or check the incoming shuttle. The binder 7 is mounted for 10 floating movement, by which I means that it is not confined to pivotal movement on a fixed axis, but is capable of both pivotal movement and rectilinear movement or a combination of both, so as to engage the shuttle over a comparatively 15 large area. The floating movement of the binder may be obtained in any desired manner. As shown on the drawing, such movement is obtained by providing the outer end of the binder with a head portion which is slotted at 8 to receive 20 a fulcrum pin 9 which is fixed to the lay adjacent the outer end thereof and on which the binder may both pivot and slide laterally of the shuttle box.

25 Suitable spring means are provided for yieldingly opposing movement of the inner end of the binder by the incoming shuttle. The particular means shown is comprised of a conventional binder spring 10 having its outer end fixed to the lay and its inner end bearing against the binder 35 adjacent the inner end 11 of the latter. Pivotal movement of the binder by the incoming shuttle serves to operate the loom protection mechanism of which only the finger 12 is shown. The further, or floating movement of the binder by the 40 shuttle is opposed by the friction means of the present invention.

45 The binder is provided with a curved friction surface which projects exteriorly of the shuttle box. In the present embodiment such surface is comprised of the curved surface of a metal plate member 13 which is fixed to the outer end of the binder on the side thereof opposite to its shuttle engaging surface. A flexible strap 14 frictionally engages the said curved friction surface, one end 50 of the strap being fixed to the lay while the other end thereof is yieldingly connected to the binder.

55 The fixed end of the strap preferably extends laterally of the lay outwardly of the picker 6 and is fastened to a bracket 15. The bracket may be

adjustably secured to the lay by a bolt and slot connection as shown on the drawing. When the bracket is adjusted to its innermost position the friction strap extends across the path of the 5 picker so that the strap will be engaged and tightened by the picker when the latter is moved outwardly by the shuttle. The other end of the friction strap is fastened to one end of a coiled tension spring 16. This spring may be partly 10 housed in an aperture 17 (Fig. 5) formed in the binder, the end of the spring being looped about a pin 18 in the binder. The details of the spring means by which the friction strap is connected to the binder are not essential, the essential features being that the connection is yielding and 15 that it acts in a direction to pull the strap against the curved friction surface.

When the shuttle is absent from the shuttle box the outer end of the binder occupies the position shown by Fig. 1 while the inner end of the 20 binder is positioned forwardly from its Fig. 1 position. The incoming shuttle first moves the inner end of the binder to operate the protection mechanism. The outer end of the shuttle engaging 25 surface of the binder normally projects into the shuttle box, Fig. 1. The entering shuttle must, therefore, push the outer end of the binder laterally of the shuttle box, which movement is opposed by the friction of the strap 14 30 on the curved friction surface on the binder. Such movement is also opposed by the spring 16, as will be apparent when it is considered that the spring is stretched as the outer end of the binder is moved by the shuttle.

35 The floating binder as thus described engages the incoming shuttle over a comparatively large area and accordingly provides a greatly improved checking action. The use of a friction strap yieldingly connected to the binder provides adequate resistance to the entrance of the shuttle 40 into the shuttle box but provides very much less resistance to the picking of the shuttle out of the box. That is, entrance of the shuttle into the 45 box is opposed by the action of the spring 16 and the friction of the strap, but after the shuttle is fully boxed the spring and friction, in effect, work against each other and thus apply very little pressure to the binder.

Having fully disclosed the preferred embodiment of my invention, I claim:

50 1. In a fly shuttle loom, the combination of a lay, a shuttle, a shuttle box having a binder adapted to be engaged and moved laterally of the shuttle box by the incoming shuttle, said binder being provided with a curved friction surface projecting 55 exteriorly of the shuttle box, a flexible friction strap engaging said surface, means fixing one end of said strap to the lay, and spring means yieldingly connecting the other end of the 60 strap to the binder, said spring means acting in a direction to pull said strap against said friction surface to thereby frictionally oppose said movement of the binder by the shuttle.

2. In a fly shuttle loom, the combination of a lay, a shuttle, a shuttle box, a floating binder adapted to be engaged and moved laterally of the shuttle box by the incoming shuttle, spring means 5 yieldingly opposing movement of the inner end of the binder by the shuttle, said binder being provided adjacent its outer end with a curved friction surface projecting exteriorly of the shuttle box, a flexible friction strap engaging said surface, means fixing one end of said strap to the 10 lay, and spring means connecting the other end of the strap to the binder, said spring means acting in a direction to pull said strap against said surface whereby the strap frictionally opposes movement of the outer end of the binder by the 15 incoming shuttle.

3. In a fly shuttle loom, the combination of a lay, a shuttle, a shuttle box, a fixed pivot adjacent the outer end of the shuttle box, a floating binder having a slotted head in which said pivot 20 engages, a binder spring yieldingly opposing pivotal movement of the inner end of said binder about said pivot, and friction means opposing sliding movement of said slotted head on said pivot, said friction means being comprised of a 25 flexible strap frictionally engaging a friction surface formed on said binder and a spring pulling said strap against said friction surface.

4. In a fly shuttle loom, the combination of a lay, a shuttle, shuttle picking means including a 30 picker, a shuttle box having a binder adapted to be engaged and moved laterally of the shuttle box by the incoming shuttle, said binder being provided with a curved friction surface projecting 35 exteriorly of the shuttle box, a flexible strap frictionally engaging said surface to thereby frictionally oppose said movement of the binder by the shuttle, spring means yieldingly connecting one end of said strap to the binder, and a bracket to which the other end of the strap is fixed, said 40 bracket holding said strap in position to be engaged and tightened by the picker as the latter is moved outwardly by the shuttle.

5. In a fly shuttle loom, the combination of a lay, a shuttle, a shuttle box, a floating binder 45 having a shuttle engaging surface on one side thereof, said binder being adapted to be engaged and moved laterally of the shuttle box by the incoming shuttle, a binder spring acting on the binder adjacent the inner end of the latter, a 50 curved friction plate fixed to the outer end of said binder on the opposite side of the latter from said shuttle engaging surface, a flexible friction strap frictionally engaging the curved surface of said plate, means fixing one end of said strap to the 55 lay, and a spring connecting the other end of the strap to the binder, said spring acting in a direction to pull said strap against said plate whereby the strap frictionally opposes movement of the outer end of the binder by the shuttle. 60

CARL D. BROWN.
